UNITED STATES PATENT OFFICE.

WALTER M. CROSS, OF KANSAS CITY, MISSOURI, ASSIGNOR TO GASOLINE PRODUCTS COMPANY, A CORPORATION OF SOUTH DAKOTA.

PROCESS OF TREATING HYDROCARBONS AND PRODUCTS DERIVED THEREFROM.

1,203,312.

Specification of Letters Patent. Patented Oct. 31, 1916.

Application filed January 9, 1915. Serial No. 1,281.

To all whom it may concern:

Be it known that I, WALTER M. CROSS, a citizen of the United States, residing in the city of Kansas City, county of Jackson, and 5 State of Missouri, have invented certain new and useful Improvements in Processes of Treating Hydrocarbons and Products Derived Therefrom, of which the following is a specification.

10 This invention relates to improvements in processes of treating hydrocarbons and products derived therefrom and more particularly to a process adapted to convert the heavy hydrocarbons into lighter hydrocarbons and to produce new products from those treated.

15 Among the salient objects of the invention are to provide a process in which the hydrocarbons may be subjected to both heat and vapor pressure while in motion; to provide a method of treating hydrocarbon oils and the like wherein relatively small streams are successively subjected to the action of heat; to provide an apparatus and process where- 20 by a large body of the oil may be heated in a closed converter while at no time subjecting the entire body of oil directly to the action of the heat; to provide a process whereby higher boiling point hydrocarbons 25 can be safely and economically converted to lower boiling point hydrocarbons; and in general to provide an improved process for treating hydrocarbons and products derived therefrom.

30 In the particular form of apparatus shown in the drawings, Figure 1 shows a general view of the apparatus. Fig. 2 shows a vertical section of the furnace.

1 designates a furnace having the usual 35 fire box 2, above which is located a series of tubes 3 opening at their opposite ends into hollow end plates 4 and 5. A plurality of baffle plates 6 and 7 are employed in the furnace for forcing the hot gases to travel 40 back and forth along substantially the entire length of the tubes 3 before passing to the stack 8. Opening into the lower portion of the end plate 4 is an inlet 9, connected to a source of supply in a manner hereinafter 45 described, and at the upper end of the end plate 5 is an outlet 10 connected by a conduit 11 with converter tank 12. Leading from this converter tank is a pair of discharge pipes 13 and 14, the latter of which

connects with a reheater 15 and the former 55 is connected by a T coupling 16 to the supply pipe 17 and the inlet pipe 9.

In the employment of this apparatus it is contemplated that the substance treated will circulate from the converter tank 12 through 60 the furnace tubes 3 and back into the converter tank. In order to cause this circulation a pump 18 is employed for forcing the oil through the inlet 9; as shown, this pump is driven by a motor 19, both pump and 65 motor being mounted on a common base 20. Passage through the various pipes is controlled by suitable valves; the pipe 13 being provided with a cutoff valve 21 located intermediate its connection with the coupling 70 16 and the tank 12, while a similar cutoff valve 22 is positioned in the pipe 14 for controlling the passage from the converter tank 12 to the reheater 15. The supply pipe 17 also has a cutoff valve 23, this valve being 75 for the purpose of controlling the admission of the oil to the apparatus from the source of supply.

In starting the process the tubes 3 and converter tank 12 are only partially filled so 80 as to leave a relatively large vapor space above the body of the oil, this space being preferably 50 per cent. or more of the entire capacity of the converter. When filling the tank the valves 21 and 22 are closed and the 85 valve 23 opened. The oil then flows through the inlet 9 either by means of gravity pressure on the source of supply or by the action of the pump 18. When a desired amount of oil is supplied to the apparatus the valve 23 90 is closed and the valve 21 opened. The pump then serves to draw the oil from the tank 12 through the pipe 13 and forces it through the inlet 9 into the end chamber 4 and through tubes 3. Here the oil in passing 95 through the tubes 3 to the end chamber 5 and outlet 10 is subjected to the action of the furnace heat, and after passing into the outlet 10 is returned to the converter tank 12. This cycle of operation is continued until the desired temperature and pressure are reached, attention being called to the fact 100 that the contents of the converter tank 12, tubes 3 and the intermediate connections are under the vapor pressure of the hydrocarbons and their conversion products. The tank 12 is provided with the usual pyrometer 105 (not shown) pressure gage 25 and safety

valve 26, whereby the temperature and pressure of the contents of the converter can be observed.

While the apparatus disclosed is not limited to employment with the particular process described, and vice versa, I will describe its use in carrying out a process in which hydrocarbons are heated in the closed converter tank 12 and tubes 3 until the temperature is such that there is produced a vapor pressure of the hydrocarbons and their conversion products out of proportion to the rise in temperature. The treatment is preferably continued in the converter until there is no longer produced a vapor pressure out of proportion to the temperature. The contents of the converter tank 12 are then allowed to cool and are drawn off through the pipe 14 into the reheater 15, the valve 21 being closed and the valve 22 opened for this purpose. The temperature of the contents of the reheater 15 is then raised to the point at which the desired hydrocarbons will be vaporized and will pass through the pipe 28 into the condenser 29 from which they are drawn off through the outlet 30. The condenser 29 is of the usual construction and is provided with an inlet 31 through which a cooling fluid is admitted and withdrawn through the outlet 32. After the contents of the condenser have been removed the temperature of the reheater may be raised and hydrocarbons having a higher boiling point vaporized and condensed in the same manner.

While the temperatures and pressures at which the process is carried out will vary through a wide range owing first to the substance treated, and second to the character of the products desired, the following temperatures and pressures have been employed to produce the desired results. If the converter tank 12 is partially filled with gasoline in the manner heretofore described and the temperature raised so that the pressure increases from slightly above that of one atmosphere to 40 atmospheres, it is noticed that there is no increase of a vapor pressure out of proportion to the rise in temperature, that is, as the temperature has increased there is simply a corresponding increase in pressure. If, however, kerosene is treated in the same manner, the pressure rises in proportion to the rise in temperature until a temperature of nearly 300 deg. centigrade is reached, after which there is an increase in pressure entirely out of proportion to the increase in temperature. Similarly, when treating 26 deg. Baumé petroleum residuum, there is a noticeable increase of pressure out of proportion to the increase of temperature when the latter is between 300 and 325 deg. centigrade, that is, at those temperatures the pressure rises rapidly with slight increase in the temperature. While

these temperatures and pressures are only approximate and vary greatly according to the substance treated and the products desired, it is noticed that in each case there is a certain temperature below which the rise in pressure corresponds to the rise in temperature, and above which the rise in pressure is out of proportion to the rise in temperature. While the exact nature of the reaction is not understood, it is obvious from the above observations that when hydrocarbons are treated by this process new products are produced rapidly above the breaking point but are not produced below such temperature, and in treating any particular substance the operator by the proper observations of temperature and pressure determines what the breaking point is. From this point the temperature is preferably raised very slowly, since in making gasoline from kerosene it is found that a sweeter product is derived where the increase in temperature above the breaking point is very slow. The process is preferably continued until there is no longer any rise in pressure out of proportion to the rise in temperature. The contents of the converter are then allowed to cool without releasing the pressure except such a decrease as results from the cooling. The product of the converter is then drawn off into the reheater and the temperature in the reheater maintained at a point which will vaporize the product desired. By varying the temperature in the reheater different products can be condensed and separated.

By the employment of a separate converter tank connected to the tubular heating element, I am enabled to treat a large body of oil without subjecting the apparatus to the excessive strain and resultant danger of explosion which is present when a large body of oil is subjected in bulk to the action of heat. Moreover, the substances treated are kept in constant circulation while the construction of the apparatus is such as to permit a relatively large vapor space above the main body of the oil.

As clearly shown in Fig. 2, end plates 4 and 5 are provided with a series of screw plugs 33 and 34 which can be removed to clean out the respective tubes or to withdraw one of the tubes and insert a new one in case one of the tubes gives way. These end plates are secured in position by a plurality of tie rods 35, the entire construction being such that the device is readily assembled and can be conveniently repaired.

While I have stated certain temperatures and pressures at which gasoline, kerosene and fuel oil can be treated by my process, I do not desire to limit my invention to such substances or the temperatures and pressures mentioned or in any manner except as specified in the appended claims.

I claim as my invention:

1. The process of treating hydrocarbons which consists in charging a converter only partially filled with hydrocarbons so as to leave a vapor space above the main body of the oil, subjecting successive portions of the oil to heat until the temperature is such that there is produced a vapor pressure of the hydrocarbons and their conversion products out of proportion to the temperature, and in allowing the contents of the converter to cool while maintaining the vapor pressure except as reduced by the cooling.

2. The process of treating hydrocarbons, which consists in charging a converter only partially filled with the hydrocarbons so as to leave a vapor space, subjecting a relatively small stream of the hydrocarbons to heat, circulating the hydrocarbons so as to cause successive portions thereof being subjected to the heat, the hydrocarbons being subjected to such a temperature that there is produced a vapor pressure of the hydrocarbons and their conversion products out of proportion to the temperature.

3. The process of treating hydrocarbons which comprises compelling a bulk supply of the hydrocarbons to pass through a relatively small stream, subjecting such stream to the action of heat and causing the continued circulation of the treated substance through the bulk supply and the small stream while maintaining both under the vapor pressure of the hydrocarbons and their conversion products.

4. The process of treating hydrocarbons, which consists in charging a converter only partially filled with the hydrocarbons so as to leave a vapor space above the main body of the oil, successively subjecting relatively small portions of the hydrocarbons to heat

and returning the heated portions to the bulk supply, the hydrocarbons being subjected to such a temperature that there is produced a vapor pressure of the hydrocarbons and their conversion products out of proportion to the temperature, allowing the contents of the converter to cool, conducting in vapor form the portion of resultant products having the desired boiling point and condensing such vapors.

5. The process of treating hydrocarbons, which comprises providing a bulk supply, providing a heating station, passing the material from the bulk supply through the heating station in the form of a plurality of sets of separate small streams, heating said streams at said station and causing the continued circulation of the treated substance through the bulk supply and small streams while maintaining both under the vapor pressure of the hydrocarbons and their conversion products.

6. The process of making gasolene-like products from hydrocarbons of a higher boiling point than gasolene, which consists in causing a bulk supply of such higher boiling point hydrocarbons to pass in the form of a plurality of separated independent streams, each much smaller than the bulk supply, subjecting said streams to a relatively high heat and causing the circulation of the hydrocarbons through the bulk supply and the small streams while maintaining both under vapor pressure of the hydrocarbons and their conversion products.
